(57) **CLAIM**

I claim the ornamental design for the angle finder, as shown and described.

DESCRIPTION

FIG. 1 is a first top perspective view of the angle finder;
FIG. 2 is a second top perspective view thereof;
FIG. 3 is a bottom perspective view thereof;
FIG. 4 is a top view thereof;
FIG. 5 is a side view thereof;
FIG. 6 is a side view thereof showing the side opposite that shown in FIG. 5;
FIG. 7 is a bottom view thereof;
FIG. 8 is a rear view thereof; and,
FIG. 9 is a front view thereof.
In the figures, dashed lines are used to illustrate features of the angle finder which form no part of the claimed design.
